UNITED STATES PATENT OFFICE.

SWEN JOHNSON, OF HURON, SOUTH DAKOTA, AND JOHN JOHNSON, OF MISSOULA, MONTANA.

LUBRICATOR.

1,111,156.

Specification of Letters Patent. Patented Sept. 22, 1914.

Application filed May 14, 1913. Serial No. 767,701.

To all whom it may concern:

Be it known that we, SWEN JOHNSON and JOHN JOHNSON, citizens of the United States, residing, respectively, at Huron, county of Beadle, State of South Dakota, and Missoula, in the county of Missoula and State of Montana, have invented certain new and useful Improvements in Lubricators, of which the following is a specification.

Our invention relates to improvements in lubricators and is designed for use in connection with steam or other fluid pressure engines.

The primary object of our invention is the provision of a lubricator feeding device especially adapted for use with steam engines, that will be simple and inexpensive of construction, that will be automatic in its operation thereby saving the lubricant; and one that may be regulated with facility.

The invention consists essentially in certain novel features of construction and combinations and arrangements of parts whereby a device is provided in which the feed of the lubricant is constant and dependent upon the steam pressure, and which feed is automatically cut off when the steam pressure is cut off. In this connection the feeding device is especially applicable for locomotives and other engines in which the steam is shut off at intervals, and the automatic operation of the feeding device renders it peculiarly adaptable for use in connection with the air pump of a locomotive which is automatically actuated.

In the accompanying drawings we have illustrated one complete example of the physical embodiment of our invention, omitting the sight feed glass, constructed according to the best mode we have so far devised for the practical application of the principles thereof.

Figure 1 is vertical central sectional view of the device, partly in elevation, and constructed according to our invention. Fig. 2 is a bottom plan view, a portion being shown in transverse section. Fig. 3 is a side elevation of the device. Fig. 4 is a bottom plan view.

In the preferred embodiment of our invention we employ the body of the feeding device designated by the letter A to which is secured by screw threads, the open cylindrical casing B. Within the casing or

cylinder a piston head C is inclosed and adapted to reciprocate, being guided through the perforated bottom of the cylinder, by its stem C'.

The letter D designates an adjustable valve stem which is threaded in the piston head C and is formed with a small needle valve 1 at its end, and an intermediate valve 2 adapted to seat against the lower end of an opening or passage 2' in the casing A. The open bottom of the hollow stem C' through which the stem D projects is closed by a packing nut E, to prevent escape of steam, and a coiled spring F is located in the cylinder B which tends to lift the piston C from its seat 3 formed in the cylinder.

By means of the packing nut G the feeding device may be attached to the glass tube as usual, and the glass may have the usual drain valve actuated by the stem H.

Steam is admitted to the interior of the cylinder B by pipe I and passage B', and oil is admitted to the feed through the pipe J, and passages J' and J² conduct the lubricant to the glass.

A drain cock K is employed to drain the cylinder B, and L indicates the place of attachment to drain the feed glass. By means of the threaded boss a the device may be attached to an oil chamber of suitable type.

In operation, it will be understood that the piston C is lifted by means of the spring F, and by means of the piston, the valve stem D and its valves 1 and 2 are closed, preventing feed of oil through passage J², and leak of oil through passage 2' into the cylinder. When the throttle is opened and steam is admitted through the pipe I, it passes through passage B' into the cylinder and the pressure of the steam overcomes the spring F and forces down the piston C. The downward movement of the piston withdraws the stem D and the valve 1 from its seat. The withdrawal of the valve 1 permits the flow of oil through pipe J, passage J' and passage J² to the glass, from whence it is conducted to the part to be lubricated as usual. When steam

is shut off, and lubrication is unnecessary, the spring F forces the piston C from its seat 3 and closes the valve 1 to cut off the supply of oil. The stem may be adjusted by turning its threads in the cylinder to regulate the flow of oil, and when so regu-

lated the parts may be held in adjusted position.

Having thus fully described our invention, what we claim as new and desire to 5 secure by Letters Patent is:—

In a lubricator, the combination with a cylinder and a piston therein having an integral hollow stem, and a body portion provided with a steam inlet and oil passage 10 in communication with the cylinder, of a valve stem adjustable in the piston stem to close the oil passage, and a spring surrounding the piston stem and urging the piston to close the valve in the oil passage.

In testimony whereof we affix our signatures in presence of two witnesses. 15
